UNITED STATES PATENT OFFICE.

HARRY JOYCE, OF BIRMINGHAM, ENGLAND.

APPARATUS OR ARRANGEMENT FOR ASSISTING IN THE COOLING OF THE CYLINDERS OF INTERNAL-COMBUSTION ENGINES.

1,177,250.

Specification of Letters Patent. Patented Mar. 28, 1916.

Application filed January 13, 1913. Serial No. 741,846.

To all whom it may concern:

Be it known that I, HARRY JOYCE, a subject of the Kingdom of Great Britain, residing at Anderton Mills, Sydenham Road, Small Heath, Birmingham, in the county of Warwick, England, manufacturer, have invented a certain new or Improved Apparatus or Arrangement for Assisting in the Cooling of the Cylinders of Internal-Combustion Engines, of which the following is a specification.

The present invention has relation to a new or improved apparatus or arrangement for assisting in the cooling of the cylinders of internal combustion engines, and has for its object to provide an apparatus or arrangement which is simple in construction and efficient in action and which will materially assist the circulation of the water between the radiator and the cylinder jackets.

In order that this invention may be clearly understood and readily carried into practice reference may be had to the appended explanatory two sheets of drawings, upon which:—

Figure 1 is a sectional side elevation illustrating one form of the present invention. Fig. 2 is an elevation showing the fan mounted on a separate bearing to the propeller. Fig. 3 is a similar view to Fig. 1 but illustrating a worm, screw or helical blade instead of a propeller. Fig. 4 is a view showing diagrammatically one method of friction drive. Fig. 5 is a view showing diagrammatically another method of drive incorporating a jockey pulley.

In accordance with the present invention the main fan *a* which is disposed behind the radiator and suitably driven off the engine is provided with a spindle *a*¹ which is suitably journaled and is provided at its extremity with a propeller *a*² which is disposed in the pipe or tube *b* connecting the radiator to the cylinder. Thus it will be seen that in operation as soon as the engine is running the main fan *a* is caused to revolve so rotating the propeller *a*² disposed in the connecting tube *b* and thereby materially assisting the circulation of the water.

The apparatus is preferably used in conjunction with a thermo-siphon cooling arrangement to assist same and it will be obvious that should any derangement occur to the apparatus the natural circulation of the water is in no way affected.

According to one convenient construction as shown in Fig. 1, the spindle or shaft *a*¹ carrying the main fan *a* disposed behind the radiator, and also the assisting propeller *a*² arranged in the pipe *b* may be journaled in a suitable portion of the said pipe such as for instance the spindle or shaft *a*¹ may enter or pass through a stuffing box or the like *a*⁶ in the said pipe thus insuring the connection being water-tight and the pipe for this purpose is formed or bent at right angles to itself, the spindle *a*¹ lying in the horizontal portion entering the cylinder jacket while the main fan *a* lies in the same plane as the vertical portion. A bearing *b*¹ is provided in the pipe to receive the horizontal spindle. A pulley *a*³ may be mounted on the spindle for driving same off the engine.

If desired the main fan may be mounted on a separate bearing as shown in Fig. 2 and be provided with a pulley *d* and in this instance the propeller spindle *d*² is as before provided with pulley *d*³, the two pulleys being driven by an endless belt *e* embracing same and operated from the engine in the usual manner. Instead of a propeller *a*² being provided on the spindle *a*¹, a worm screw or helical blade *f* may be employed as shown in Fig. 3. According to a further modification as shown in Fig. 4 the pulley *d* on the main fan *a* and spindle *d*² carrying the propeller may be in frictional engagement or a friction pulley *e*¹ may be disposed between same, or in order that the propeller *a*² may be always in engagement or be turned by the rotation of the fan *a*, an endless band *e*³ may be employed and in order that the tension of same may be adjusted a jockey pulley *e*² may be employed as shown in Fig. 5. The spindle or shaft *a*¹ as shown in Fig. 1 may be prevented from endlong movement by means of the pulley *a*³ mounted thereon at one extremity of the bearing *a*⁶ and a small collar *a*⁴ disposed around the shaft at the extremity of the bearing *b*¹. The propeller *a*² may have two or any convenient number of blades *a*⁵ and same may be disposed in the tube *b* conducting the water to the cylinder or cylinders *c* or in the tube conducting the water away from the cylinders the blades of the propeller being of course fixed so that they force the water into the cylinder in the former case, and away from the cylinder in the latter case.

If desired the main fan mounted behind

the radiator may be run or driven independently of the present arrangement, in this case the shaft or spindle being provided with an external pulley or the like which is suitably driven off the engine to rotate the internal propeller as before.

What I claim as my invention and desire to secure by Letters Patent is:—

1. In a water cooled internal combustion engine, the combination of a thermo-siphon cooling system having a pipe, a propeller mounted in said pipe for assisting the flow of water in the direction produced by the thermo-siphonic action, a shaft for said propeller extending through the wall of said pipe, a fan for the cooling system mounted on said shaft, and connections for driving said fan and propeller, said propeller being adapted to pass liquid therethrough when stationary whereby the thermo-siphonic action is uninterrupted.
2. In a device for assisting in the cooling of the cylinders of internal combustion engines, the combination of a water cooling system having a pipe bent at right angles, a driven fan having its axle journaled in

the bend of said pipe and extending concentrically and longitudinally within the bore of the straight portion of said pipe, a propeller mounted on said axle and adapted to operate with said fan thereby materially aiding in circulating the cooling water, and means for driving said fan.

3. In a device for assisting in the cooling of the cylinders of internal combustion engines, the combination of a water cooling system having a pipe bent at right angles, a driven fan having its axle journaled in the bend of said pipe and extending concentrically and longitudinally within the bore of the horizontal portion of said pipe, and a propeller mounted on said axle and adapted to operate with said fan thereby materially aiding in circulating the cooling water, and means for driving said fan.

In witness whereof I have hereunto set my hand in the presence of two witnesses.

HARRY JOYCE.
